UNITED STATES PATENT OFFICE.

ISAAC HERMANN, OF NEW YORK, N. Y.

DESIGN FOR AN EXHIBITION-STAND.

SPECIFICATION forming part of Design No. 23,079, dated February 20, 1894.

Application filed January 24, 1894. Serial No. 497,938. Term of patent 7 years.

To all whom it may concern:

Be it known that I, ISAAC HERMANN, of the city, county, and State of New York, have invented a new and original Design for a Mirror Exhibition-Stand, of which the following is a full, clear, and exact description.

Reference is to be had to the accompanying drawing forming a part of this specification, in which the figure is a perspective view of a mirror exhibition stand showing my design.

The leading feature of my design consists in the vertical panels A, B, disposed approximately at right angles one to the other, and the horizontal shelf-like figures C in retreat-

ing step form and partially intersecting the panels A, B; the inner corners of the shelf-like figures being in the joint between the panels and their outer corners being in diagonal lines on the panels and the latter thus each presenting an undivided half and a divided half.

I claim—

The design for a mirror exhibition stand, substantially as shown and described.

ISAAC HERMANN.
